UNITED STATES PATENT OFFICE.

JOSEF KARRER, OF ZURICH, SWITZERLAND, ASSIGNOR, BY MESNE ASSIGNMENTS, TO
GENERAL ELECTRIC COMPANY, A CORPORATION OF NEW YORK.

ARRANGEMENT FOR REGULATING STEAM-TURBINES.

1,118,355.

Specification of Letters Patent.

Patented Nov. 24, 1914.

Application filed August 14, 1911. Serial No. 644,008.

To all whom it may concern:

Be it known that I, JOSEF KARRER, citizen of Switzerland, residing at Zurich, Switzerland, have invented certain new and useful 5 Improvements in Systems of and Arrangements for Regulating Steam-Turbines, of which the following is a specification.

My invention relates to governing mechanism for elastic fluid turbines and the object of the invention is the provision of an improved governing mechanism of simple reliable construction that will effectively control the speed of the turbine as the load varies and avoid the objections incident to 15 the leakage of motive fluid through the valves to the turbine rotor.

For a consideration of what I believe to be novel and my invention, attention is directed to the accompanying description and 20 the claims appended thereto.

In the accompanying drawings illustrating some of the embodiments of my invention, Figure 1 is a diagrammatic view of the governing mechanism as applied to a turbine; Fig. 2 is a similar view of a modification of the governing mechanism of Fig. 1; Fig. 3 is a diagrammatic top view of the apparatus of Fig. 2; Figs. 4 and 5 are diagrammatic views of other modifications of 25 the invention; Fig. 6 is a sectional view of a turbine having admission valves connected to the governor in a manner similar to that shown in Fig. 1; and Fig. 7 is a sectional view similar to Fig. 6 showing an overload 30 valve in addition to the admission valves, said valves being arranged in a similar manner to those illustrated in Fig. 2.

Referring to Figs. 1 and 6, the turbine is provided with nozzles, discharging devices, or admission passages D¹, D², and D³ arranged in sets or groups, through which steam or other elastic fluid passes to the initial vanes or buckets of the turbine rotor that comprises a shaft 9 and a suitable supporting structure for the vanes or buckets carried thereby. While three groups of nozzles or admission passages are shown in Fig. 6, the invention is not limited to the exact number illustrated.

50 Steam is supplied to the turbine by a conduit 10 controlled by a throttle valve V¹. This valve is of sufficient size to pass all the necessary fluid to the turbine when wide open without undue restriction. The valve 55 is preferably connected to the piston rod 12

of a hydraulic or other fluid actuated motor 13. The admission of fluid under pressure to the motor cylinder and its exhaust therefrom to move the piston K, and its rod is regulated by a pilot valve St, whose stem 60 is pivotally connected to a lever H¹. The lever is pivotally connected at one end to an axially movable member or collar M of the speed governor R, which is driven directly or indirectly from the turbine shaft 9, the 65 other end of the lever being pivotally connected to an extension of the piston rod 12 to form a follow-up device for restoring the pilot valve to its neutral position after it has been moved from said position by the 70 governor to bring about the opening of the valve V¹ to a given extent.

When the valve V¹ is opened, steam flows from the conduit 10 to a steam chest 18 and from said chest through the nozzles or passages D¹ into the turbine, the quantity supplied to the nozzles or passages being regulated by the extent to which the governor opens the valve. If the load conditions call for the admission of more steam than can 80 be supplied through the nozzles or passages D¹ when the valve V¹ is open, the governor then begins to open the valve V² more or less to supply a regulated quantity of steam to the nozzles D². As the valve V² opens, 85 steam flows from the steam chest 18 into the nozzles or passages D¹ and also into steam chest 20 and from the last named chest through the nozzles or passages D² into the turbine. The turbine is thus supplied with steam by both sets of nozzles, 90 devices or passages D¹ and D². If there is a demand for more steam, the valves V¹ and V² being open, as already described, then the governor begins to open the valve V³ 95 more or less so that some of the steam supplied by the conduit 10 passes through the steam chests 18 and 20 in series to the steam chest 23 and enters the turbine through the nozzles, devices or passages D³. 100 Under this condition of operation steam enters the turbine through all of the nozzles, being supplied to the several steam chests in series from the conduit 10, and the first two groups of nozzles receive a full supply 105 while the last nozzles receive a more or less full supply according to the extent to which their controlling valve is opened by the governor. If the load decreases the governor acts to close the valves in the reverse order, 110

i. e., the valve V^3 is closed first, then the valve V^2 , and finally the valve V^1 begins to close, the extent to which the valves are closed depending of course upon the magnitude of the change in load.

The stems of the valves V^2 and V^3 are pivotally connected to the lever H^2 , one end of which is connected to the extension of the piston rod 12, while the other end is fulcrumed at the point L on a support such as a bracket 24 secured to the turbine casing. Fig. 1 also shows an overload valve V^4 which is so connected to the lever H^2 that it opens subsequently to the valve V^3 to admit live steam to an intermediate or low pressure stage of the turbine when the load increases beyond that which can be carried by the steam supplied by all of the other valves. To avoid complication in the drawings this valve is not shown in Fig. 6, but its arrangement and operation will, it is thought, be clearly understood from the foregoing description and the drawings by any person skilled in the steam turbine art.

The turbine shown in Figs. 2 and 7 is equipped with valves V^1 , V^2 and V^3 , similar to the valves V^1 , V^2 and V^3 of Fig. 1. Its steam chests, nozzles, governor, pilot valve and motor are similar to those of the turbine illustrated in Fig. 6. In Figs. 2 and 7 is also shown an overload valve V^4 , for admitting live steam from the steam chest 28 to one of the intermediate or lower pressure stages of the turbine through nozzles, devices, or suitable passages. The stems of the valves V^1 , V^2 and V^3 are connected to the lever H^2 having a pivotal connection at one end with the extension of the piston rod 12 of the motor 13. During the opening of the valves V^1 , V^2 and V^3 , the lever fulcrums about the point P^4 on the stem of the valve V^4 which is held against its seat by the spring F, or some equivalent device. It could be held on its seat by its own weight or by steam pressure if desired. After the governor has opened the valves V^1 and V^2 , it then moves the lever H^2 farther about its pivot P^4 , if the load continues to increase, and opens the valve V^3 by pushing it downward until the engagement of the valve V^3 on its casing or the action of the stop 32, Fig. 7, prevents further opening of the valve. Then the lever H^2 begins to turn about the pivot P^4 as a fulcrum and opens the valve V^4 . The governor closes the valves in the reverse order when the load decreases.

In Figs. 1 and 2, the full line positions of the levers H^1 and H^2 correspond to maximum load and their dotted line positions to minimum load or no load on the turbine.

Fig. 3 is a diagrammatic top view of the governing mechanism of Figs. 2 and 7 showing how the governor, the pilot valve V^1 , and the lever H^1 can be arranged in a

different plane from the lever H^2 and the admission valves, the line of intersection of the two planes coinciding with the axis of the valve V^1 and the motor 13.

By means of this governing mechanism it is possible in a simple manner to operate valves in the lower stages of the turbine. Fig. 4 shows an example of the adaptation of the governing mechanism to a turbine having the admission valves V^5 and V^6 operated by the levers H^3 and H^4 for admitting live steam to some of the intermediate and low pressure stages. The lever H^3 is connected to the rod of the piston K and turns about the fulcrum L^3 . Said lever H^3 80 turns operates the lever H^4 about the fulcrum L^4 .

Fig. 5 shows a modification of the apparatus of Fig. 4 in which only one additional valve V^7 for admitting steam to a low pressure or intermediate stage is provided. This valve is operated by the lever H^3 .

From the foregoing it will be seen that the admission valves are arranged in series relation as to the flow of steam and that each valve receives its steam at full admission pressure when it is in operation. Through each of the admission valves passes, not only the steam for its corresponding group of nozzles or passages, but also the steam for all of the subsequent nozzles that are in operation. The steam passes serially through all of the valves and the steam chests under full load conditions and hence when the load is light the motive fluid is cut off from the later valves. Thus the leakage of but one valve can affect the operation of the turbine. Owing to the rather common use of superheated steam in turbines and the consequent difficulty of keeping the valves steam-tight this arrangement assists materially in improving and maintaining the efficiency of the turbine because such leakage steam cannot be effectively used in the turbine. This is made apparent by the fact that a small amount of steam passing through a nozzle or other discharge device cannot act effectively. The valves are actuated in a simple manner by one or more levers that are preferably moved by the same hydraulic or other pressure motor that operates the first or main admission valve, while the governor has merely to do the work of operating the relatively small pilot valve. The number of pivots can be reduced as illustrated by having the overload valve serve as a pivotal point until all the other valves are opened when any one of said valves may act as the pivot.

V^1 may be termed the main regulating valve, and V^2 , V^3 , etc., the partial regulating valves because all of the motive fluid has to pass through the valve V^1 before the valves V^2 , V^3 , etc. can act thereon. It will be seen

that the sizes of the valves successively decrease from V^1 toward V^4 . This is due to the fact that the amount of steam to be handled by the valves successively decreases. It will also be seen that the movements of the several valves differ one from the other, the valve having the greater movement also being the largest so as to freely pass the steam.

10 It is obvious that any desired number of valves for admitting steam to the intermediate and low pressure stages can be arranged at suitable points on the turbine and that the lever transmissions, pivotal points, etc., can be constructed in any other suitable manner. The different stages of the turbine can also be arranged on one or more shafts as preferred.

15 In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

I claim:

1. In a governing mechanism for elastic fluid turbines, the combination of a plurality of valves arranged in series relation as to the flow of fluid, said valves regulating the admission of motive fluid to the turbine, a motor, a controller for the motor, a speed responsive device that actuates the controller, means actuated by the motor for opening and closing the valves in successive order, and a device for preventing overtravel of the motor.

2. In a governing mechanism for elastic fluid turbines, the combination of a plurality of valves arranged in series relation as to the flow of motive fluid, said valves regulating the admission of fluid to the turbine, a motor, a controller for the motor, a means mechanically uniting the valves that is actuated by the motor and moves said valves in predetermined sequence, a speed responsive device that actuates the controller of the motor, and a device for preventing overtravel of the motor.

3. In a governing mechanism for elastic fluid turbines, the combination of a plurality of valves arranged in series relation as to the flow of fluid, said valves regulating the admission of motive fluid to the turbine, a separate chest for each valve, a motor, a controller for the motor, a pivoted means that is attached to the valves and also to the moving member of the motor, said means actuating the valves successively, a governor that actuates the controller, and means for preventing overtravel of the motor.

4. In a governing mechanism for an elastic fluid turbine, the combination of a plu-

rality of valves for regulating the admission of motive fluid to the turbine, a separate chest for each valve, said chests being serially connected, a motor, a controller for the motor, a lever that is pivotally attached to the stems of the valves and to the moving element of the motor, a speed responsive device that actuates the controller, and a connection between the lever and the controller to prevent over-travel of the motor.

5. In a governing mechanism for an elastic fluid turbine, the combination of a main regulating valve, one or more partial regulating valves, said valves being arranged in series with respect to the passage of the working fluid, a lever system for actuating main and partial regulating valves, a motor that moves the lever system, a speed governor, and means actuated by the speed governor for controlling the action of the motor.

6. In a governing mechanism for an elastic fluid turbine, the combination of a main regulating valve, a partial regulating valve arranged in series with the main valve respecting the passage of working fluid, an overload valve which is normally closed, an actuator that is common to the valves, a connection between the overload valve and said actuator which acts as a pivot for the actuator until all the partial regulating valves have opened, and a second pivotal connection between one of the valves and the actuator which acts as a pivot therefor to permit the opening of the overload valve.

7. In a governing mechanism for an elastic fluid turbine, the combination of a plurality of valves arranged in series relation as to the passage of motive fluid, said valves regulating the admission of motive fluid to the turbine, a lever that is common to the valves for actuating them successively, a fluid motor that is connected to the lever for actuating it, a pilot valve controlling the motor, a speed governor, and a means that connects a movable part of the governor and the pilot valve to said lever.

8. In a governing mechanism for an elastic fluid turbine, the combination of a plurality of normal load valves, an overload valve that controls the admission of motive fluid to a region of intermediate pressure in the turbine, separate chests for the valves, all of said valves and chests being arranged in series relation with respect to the passage of motive fluid, means for opening the normal load valves and then the overload valve, a fluid motor acting through said means to first actuate the normal load valves and then the overload valve upon an increase of load on the turbine, and a governor means for the motor.

9. In a governing mechanism for elastic fluid turbines, the combination of a plurality of valves, separate chests for the valves that are displaced one from the other and

are serially connected as to the passage of motive fluid, lever systems for actuating the valves, a fluid actuated motor that is common to said systems, a pilot valve controlling the motor, a governor for moving the pilot valve, and a connection between one of the lever systems and the pilot valve to prevent over-travel of the motor.

10. In a governing mechanism for turbines, the combination of a plurality of valves serially arranged as regards the passage of motive fluid, a separate casing and stem for each valve, an actuator that is common to the valves and is located outside of the casings, fulcra for the actuator which are supported by the exposed stems of said valves, and means including a stop for one valve which permits the shifting of the fulcrum of the actuator from one stem to another as the load conditions change.

11. In a governing mechanism for turbines, the combination of a plurality of valves serially arranged in respect to the passage of motive fluid, a separate casing

for each valve, a lever that is common to 25 the valves and is located outside of the fluid space, fulcra for the lever, means including a stop for permitting the shifting of the fulcrum of the lever from one point to another, means for moving the lever, and 30 a governor for controlling the action of said means.

12. In a governing mechanism for turbines, the combination of a plurality of admission valves arranged in series relation as 35 to the flow of fluid, said valves differing in size and length of travel, the largest valve having the longest travel and passing the greatest amount of fluid, a means for actuating the valves, and a governing device for 40 said means.

In testimony whereof, I affix my signature in presence of two witnesses.

JOSEF KARRER.

Witnesses:

DAVID KRIESEL,
EMIL C. REDINGER.

It is hereby certified that in Letters Patent No. 1,118,355, granted November 24, 1914, upon the application of Josef Karrer, of Zurich, Switzerland, for an improvement in "Arrangements for Regulating Steam-Turbines," an error appears in the printed specification requiring correction as follows: Page 2, line 80, for the letter "n" read *in*; and that the said Letters Patent should be read with this correction therein that the same may conform to the record of the case in the Patent Office.

Signed and sealed this 5th day of January, A. D., 1915.

[SEAL.]

R. F. WHITEHEAD,

Acting Commissioner of Patents.
